Primary Examiner — Garth Rademaker*Assistant Examiner* — Fitzgerald L Butac(74) *Attorney, Agent, or Firm* — Thompson Hine LLP(57) **CLAIM**

The ornamental design for a drill bit, as shown.

DESCRIPTION

FIG. 1 is an end view of the design;

FIG. 2 is a side view of the design of FIG. 1;

FIG. 3 is a first perspective view of the design of FIG. 1; and, FIG. 4 is a second perspective view of the design of FIG. 1. The broken lines show portions of a drill bit that form no part of the claimed design.

1 Claim, 4 Drawing Sheets(56)
